CONVERTIBLE TABLE

Auburn G. Van Syoc, Belding, Mich., assignor to
Lu Van, Incorporated, Belding, Mich.

Filed Mar. 10, 1970, Ser. No. 21,840

Term of patent 14 years

Int. Cl. D6—03

U.S. Cl. D6—3

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective end view of a convertible table showing my new design in the form of a table;

FIG. 2 is a perspective side view of the structure illustrated in FIG. 1;

FIG. 3 is a top plan view of the structure illustrated in FIG. 1;

FIG. 4 is an end elevational view of the structure illustrated in FIG. 1;

FIG. 5 is a side elevational view of the structure illustrated in FIG. 1;

FIG. 6 is a bottom view of the structure illustrated in FIG. 1;

FIG. 7 is a perspective end view of the structure illustrated in FIG. 1, showing the unit with the top reversed for use in the form of a stool;

FIG. 8 is a perspective side view of the structure illustrated in FIG. 7;

FIG. 9 is a top plan view of the structure illustrated in FIG. 7;

FIG. 10 is an end elevational view of the structure illustrated in FIG. 7;

FIG. 11 is a side elevational view of the structure illustrated in FIG. 7;

FIG. 12 is a bottom view of the structure illustrated in FIG. 7.

I claim:

The ornamental design for a convertible table, as shown.
